[57] CLAIM

The ornamental design for a housing for a hedge trimmer, as shown and described.

DESCRIPTION

FIG. 1 is a left rear perspective view of a housing for hedge trimmer according to the present invention;

FIG. 2 is a left side elevation view thereof;

FIG. 3 is a front elevation view thereof;

FIG. 4 is a rear elevation view thereof;

FIG. 5 is a right side elevation view thereof;

FIG. 6 is a top plan view thereof; and,

FIG. 7 is a bottom plan view thereof.

The broken line showing of a cutter and a debris shield are for illustrative purposes only and form no part of the claimed design.
